UNITED STATES PATENT OFFICE.

THOMAS H. SEELY, OF MALDEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SEWING MACHINE.

1,355,856.

Specification of Letters Patent. Patented Oct. 19, 1920.

Application filed December 22, 1916. Serial No. 138,399.

To all whom it may concern:

Be it known that I, THOMAS H. SEELY, a citizen of the United States, residing at Malden, in the county of Middlesex and State of Massachusetts, have invented certain new and useful Improvements in Shoe-Sewing Machines; and I do hereby declare the following to be a full, clear, and exact description of the invention, such as will enable others skilled in the art to which it appertains to make and use the same.

This invention relates to wax thread shoe sewing machines of the class employing a curved hook needle and a looper, and more particularly to looper heating devices for such machines.

The looper employed in this class of machine has a compound movement imparted thereto to carry the thread about the needle, and this necessitates mounting the looper so that it may be actuated in two different planes. In such machines it is desirable to keep the thread hot up to the time that it is incorporated in the seam, so that the wax with which the thread is impregnated will then be in proper condition for the formation of a satisfactory tight seam. The looper should therefore be kept at a fairly high temperature, so that the thread will not become chilled as it passes along the looper arm or shank and through the eye of the looper, and will reach the work in proper condition for the formation of the seam. On account of the manner in which the looper must be mounted in order to enable the proper movements to be imparted thereto, it has been a difficult matter in machines of this class to heat the looper in a satisfactory manner.

The objects of the present invention are to improve the construction and mode of operation of looper heating mechanisms for wax thread curved hook needle shoe sewing machines, and to provide for such machines, a novel looper heating mechanism which will maintain the looper at a substantially uniform high temperature in a reliable manner.

With this object in view, the invention consists in the novel and improved constructions, arrangements and combinations of parts hereinafter described and particularly

pointed out in the claims, the advantages of which will be appreciated by those skilled in the art.

55

The features of the invention will be readily understood from the accompanying drawings illustrating a machine embodying the invention in its preferred form, and the following detailed description of the construction therein shown.

60

In the drawings, Figure 1 is a view in side elevation of the forward portion of the head of an inseam shoe sewing machine embodying the invention; Fig. 2 is a detail view in side elevation illustrating particularly the looper heating mechanism of the machine; Fig. 3 is a detail view of the mechanism illustrated in Fig. 2, looking in the direction of the arrow, Fig. 2; and Fig. 4 is a detail sectional view taken substantially on the line 4—4 of Fig. 2.

65

The invention as illustrated in the drawings is embodied in a wax thread curved hook needle sewing machine for sewing inseams of boots and shoes. This machine comprises a curved hook needle 2, an awl or feed point 4, a looper 6, a thread finger 8, a welt guide 10, and a back rest 12. With the exception of the looper, all of the above mentioned parts have substantially the same construction, arrangement and mode of operation as the corresponding parts of the machine illustrated in the patent to Eppler, No. 1,108,560, dated August 25, 1914.

70

The looper is secured by means of a set screw 14 in a socket in a lever 16 pivoted upon a shaft 18 mounted in a bracket 20 secured to the forward end of the looper actuating slide 22, and extending downwardly from the slide toward the sewing point, as clearly shown in the drawings. Forward and rearward movements in a plane parallel with the plane of the needle are imparted to the looper by the reciprocation of the slide 22, and movements are imparted to the looper in a plane perpendicular to the plane of the needle by the oscillation of the looper lever 16 on the shaft 18, these movements occurring in proper timed relation to each other to carry the looper about the needle. Upon the rear end of the slide 22 is mounted a cam roll 24 which engages in a cam groove in a cam disk attached to the main shaft 26

of the machine. Through the action of the cam groove on the roll 24 reciprocatory movements are imparted to the slide. The mechanism for oscillating the looper lever 16 comprises a rock shaft 28, and arm 30 mounted on the forward end of the rock shaft, and a link 32 connecting the arm 30 with the looper lever. Upon the rear end of the rock shaft 28 is mounted an arm 34 carrying a cam roll 36 engaging a cam groove in a cam disk mounted on the main shaft 26 of the machine. By the action of the cam groove on the cam roll 36 through the connection described the looper lever is oscillated on the shaft 18 in timed relation to the forward and rearward movements thereof imparted by the slide 22 to give the proper movements to the looper.

The slide 22 contacts at its lower edge or face with a wear plate or gib 38. This wear plate rests upon the upper ends of abutment screws 40 threaded into the frame. The wear plate may be adjusted vertically to take up wear by a suitable adjustment of the abutment screws 40. It will be noted that a vertical adjustment of the wear plate will also result in a vertical adjustment of the slide 22.

The bracket 20 extends downwardly from the forward end of the slide 22, and is formed with a seat 42 to receive the looper heater. The looper heater consists of a block 44 mounted on the forwardly projecting frame plate 46, and shaped to fit the seat 42 on the bracket 20. The plane portions of the engaging surfaces of the heating block and the bracket 20, and the elements of the curved portions of these surfaces are substantially parallel with the direction of reciprocation of the slide 22, so that the heating block does not interfere with the reciprocation of the bracket 20 with the slide 22, and there is no tendency of the bracket to move out of contact with the heating block during the movements of the slide. The seat for the heating block is so formed as to furnish a comparatively large area of surface contact between the heating block and the bracket for the transmission of heat from the block to the bracket. As shown in the drawings, the bracket 20 contacts with the heating block at the side thereof, and is curved about the lower end of the block.

The heating block 44 is mounted between the parallel guides 48 on the frame plate 46. These guides are arranged substantially perpendicular to the guideway for the slide, so that the block can move between the guides in a direction substantially perpendicular to the direction of movement of the slide. The block is held yieldingly in engagement with the bracket 20 by means of a coiled spring 50 seated at its upper end in a recess in a projection 52 on the frame plate 46, and at its lower end in a suitable bore in the heat-

ing block. By means of this spring a good heat conducting contact is maintained between the heating block and the bracket 20 during the reciprocation of the bracket with the slide 22.

The heat transmitted from the heating block 44 to the bracket 20 will heat the bracket to and maintain the same at a comparatively high temperature. In order that the heat may be transmitted rapidly and efficiently to the looper lever 16 and to the looper mounted thereon, the bracket 20 is formed with parallel flanges or ribs 54 between which the looper lever 18 is mounted. The ribs 54 are spaced and the looper lever is constructed so that the lever fits closely between the ribs. The lever therefore during its oscillatory movements on the shaft 18, will be in contact or substantially in contact with both of the ribs. As clearly shown in the drawings, the width of these ribs is such that they extend over and contact with very nearly the whole of each lateral face of the looper lever. This construction furnishes a comparatively large area of contact between the ribs and the lever for transmitting heat from the bracket 20 to the lever. It will be noted that with this arrangement of the heating block relative to the bracket 20 and the looper lever, the heating block contacts with the bracket 20 close to the engaging surfaces of the bracket and the looper lever, and that the heating block is located close to the looper itself, so that heat is transmitted by conduction rapidly and with little loss from the heating block to the looper. By the heat transmitted from the heating block 44 through the bracket 20 to the looper lever 16 and to the looper mounted thereon, the looper will be kept at a comparatively high temperature in a reliable manner during the sewing operation.

The heating block 44 may be heated in any suitable manner or by any suitable heating medium. In the construction illustrated in the drawings the heating block is arranged to be heated by steam. To this end the block is formed with a steam chamber 56 which is supplied with steam through an inlet pipe 58. The forward end of the inlet pipe is connected with the steam chamber by means of a short pipe section 60 threaded into the block 44, and a union 62 connecting the forward end of the inlet pipe with the pipe section 60. The rear end of the inlet pipe is connected with a bore or passageway 64 in the frame, adapted to be connected with the source of steam supply. The steam passes from the steam chamber 56 through an outlet pipe 67 connected at its forward end with the chamber 56 and extending from the heating block 44 toward the rear of the machine.

The present machine is also provided with devices for severing the thread be-

tween the shoe and the machine after the completion of a seam and for holding the severed end of the thread projecting from the thread handling devices during the first 5 part of the formation of the next seam. The devices for severing and holding the thread comprise a thread cutting knife 68 and a thread gripping device 70. The thread cutting knife is formed upon one 10 arm of a thin steel plate bent at an acute angle, as shown in Figs. 1 and 2, and secured by means of a screw 72 to the forward face of the forward rib 54 on the bracket 20. The thread gripping device 15 consists of two coöperating thread gripping jaws 74 and 76 adapted to yieldingly grip the thread placed between them. The thread gripping jaw 74 is formed upon a cylindrical block 77 secured to a rod 78 20 having two arms bent substantially at right angles to each other, one of which is secured in a split clamp 80 formed on the looper lever 16 and actuated by a clamping screw 82. The jaw 76 of the thread gripping device is formed at the end of one 25 arm of a U-shaped spring plate 84, the other arm of which is secured to the cylindrical block 77. To prevent the thread, when it is drawn between the thread gripping jaws, from passing beyond the jaws into the loop in the spring plate 84, two 30 lateral projections 86 formed upon the block 77 extend from the block across the plane of the contacting faces of the thread gripping jaws so as to form stops for the 35 thread.

It will be noted that the thread gripping jaws are spaced from the looper lever 16 and are connected therewith merely by the 40 rod 78 through which heat is transmitted by conduction from the lever to the gripping jaws. The gripping jaws will thus be maintained at a much lower temperature than that of the looper lever, with the result 45 that the wax with which the thread is impregnated will be cooled by contact with the gripping jaws. The thread therefore will not slip readily between the jaws, but the partially congealed wax will increase 50 the resistance exerted by the jaws on the thread. In the construction shown the distance between the lever 16 and the thread gripping jaws may be adjusted to regulate the heat transmitted by conduction from 55 the lever 18 to the gripping jaws by the

longitudinal adjustment of the arm of the rod 78 which is engaged in a clamp 80.

Certain features of the thread gripping and severing devices described above are covered by a divisional application, Serial 60 No. 291,294, filed April 19, 1919.

Having explained the nature and object of the invention and having specifically described a machine embodying the same in its preferred form, what is claimed is:—

1. A wax thread shoe sewing machine, having, in combination, stitch forming devices including a curved hook needle, a looper, a looper actuating slide, a bracket secured to the slide, a looper lever pivoted 70 on the bracket, and a looper heater fixed in the direction of movement of the slide and having a heat conducting contact with the bracket for heating the looper lever and the looper through the bracket.

2. A wax thread shoe sewing machine, having, in combination, stitch forming devices including a curved hook needle, a looper, a looper actuating slide, a bracket attached to the slide, a looper lever pivoted 80 on the bracket, a looper heater mounted for movement in a direction transverse to the direction of movement of the bracket and having a yielding heat conducting contact with the bracket and devices for guiding 85 the looper heater.

3. A wax thread shoe sewing machine, having, in combination, stitch forming devices including a curved hook needle, a looper, a looper actuating slide, a bracket 90 secured to the slide and having parallel spaced ribs, a looper lever pivoted on the bracket between the ribs and contacting therewith, and a looper heater engaging the bracket for heating the looper lever and 95 looper through the bracket.

4. A wax thread shoe sewing machine, having, in combination, stitch forming devices including a curved hook needle, a looper, a looper actuating slide, a bracket 100 having parallel spaced ribs secured to the forward end of the slide, a looper lever pivoted on the bracket between the ribs and contacting therewith, a rock shaft, an arm thereon, a link for connecting the arm with 105 the looper lever arranged between and held in place by the ribs, and a looper heater engaging the bracket for heating the looper lever and looper through the bracket.

THOMAS H. SEELY.
